METAL BUTTON

Harry C. Robertson, New York, N. Y., assignor to
Nathan Scher, Flushing, N. Y.

Application June 4, 1948, Serial No. 31,154

3 Claims. (Cl. 24—90)

1

This invention is a metal button of the character commonly used on ladies' dresses, uniforms and the like. They generally comprise a button body to the back of which is secured an attaching eye through which the thread may be passed to secure the button to the garment.

Heretofore these buttons have universally been made by forming the body of the button of one piece of metal, separately forming the attaching eye from another piece of metal and thereafter securing these parts to one another to form the complete button. The assembly of these separate parts is expensive and no matter how well they are fastened together, they frequently come apart after the button has been used for a time.

The object of the present invention is to produce a one piece button of superior construction embodying all the advantages of prior metal buttons but much more economical to manufacture and practically indestructible under normal usage.

Generally speaking, the button of the present invention is made from a flat blank of sheet metal, having a body portion for the formation of the button body and provided with lateral tongues or extensions adapted to be bent, through the employment of appropriate dies, to form a shank with an integral attaching eye. This eye is so formed as to eliminate sharp edges which would be apt to cut the thread and release the button from the garment. The body of the blank may be drawn, stamped or otherwise manipulated to produce a button body of the desired shape with finished edges which cannot injure the wearer or harm delicate fabrics on which the button may be sewed.

Features of the invention, other than those adverted to, will be apparent from the hereinafter detailed description and appended claims, when read in conjunction with the accompanying drawing.

The accompanying drawing illustrates different practical embodiments of the invention, but the constructions therein shown are to be understood as illustrative, only, and not as defining the limits of the invention.

Figure 1 shows a flat blank stamped from sheet metal.

Figure 1a is a section of the blank of Figure 1.

Figure 2 shows the first step in forming the blank into a button. This step constitutes a combined bending and drawing operation.

Figures 3, 4, 5 and 6 show consecutive steps in the formation of the button, Figure 6 showing the finished button.

2

Figure 6a is a transverse section through the finished button shown in Figure 6.

Figure 7 is a perspective view showing a modified form of button made according to this invention.

Figure 7a is a transverse section through the button of Figure 7.

In manufacturing one form of button according to the present invention, I start with a flat blank, such as shown in Figures 1 and 1a. Blanks of this kind are stamped from sheet metal stock of sufficiently heavy gauge to permit the material thereof to be drawn and shaped and to impart the necessary strength to the finished button.

15 The drawings show, for the purpose of illustration, the making of a circular button with a domed body. Therefore, the blank 1 has a body 2 of circular configuration with tongues 3 and 4 extending from the opposite sides of the blank.

20 These tongues are of the same length and both are perforated near their outer ends. These may be ordinary perforations. However, I prefer to make the perforation 5 of the tongue 3 in the form of an extrusion, so that the material pressed

25 out to produce this perforation is extruded to form a tubular boss 6, shown best in Figure 1a. This boss is later adapted to serve the purpose of a hollow rivet as hereinafter explained. The perforation 7 in the tongue 4 is formed by cutting out the stock and is of a diameter substantially equal to the external diameter of the tubular boss 6 of the other tongue.

30 After the blank has thus been formed, it is operated upon by a succession of bending and drawing dies to form it into the finished button.

35 The number of steps required for this manipulation of the metal will of course depend upon the metal used, the size of the button, and the design or shape of such button. However, in Figures 1-6, I have shown six steps in the formation of the button.

40 Figure 2 shows the body 2 of the blank dished or drawn to some extent, so that the dome is thereby partially formed and simultaneously the outer end portions of the tongues 3 and 4 are bent, as indicated at 8, so that said end portions are arranged in angular relation to the remainder of the tongues of which they form a part.

45 By the operation shown in Figure 3, the body of the blank is further drawn to give it greater depth. The full depth of the dome may be completed in this step.

50 The next step consists in starting the formation of an inturned flange 9 about the margin 55 of the dome, as shown in Figure 4. By this step,

the marginal portion of the dome is drawn inwardly, carrying with this marginal portion the tongues 3 and 4, so that the bent end portions of these arms are caused to approach one another. Figure 5 shows this same operation carried further so that the inturning of the flange 9 has progressed appreciably while the bent end portions of the tongues 3 and 4 are brought into close proximity with the boss 6 of the tongue 3 alined with and about to enter the perforation 7 in the arm 4.

The next step consists in completing the turning of the flange 9 until all parts of this flange preferably occupy a common plane, during which operation the boss 6 enters into and projects through the perforation 7. That portion of the boss which extends beyond the perforation is next flanged outwardly in a radial direction after the manner of manipulating a hollow rivet or grommet to bend the free end of the boss over the outer surface of the arm through which it projects, as shown best at 10 in Figure 6a. When this flange is formed, it serves to permanently lock the bent end portions of the tongues together and complete the formation of the button. The boss 6 thus functions, in effect, as a hollow rivet formed integral with one of the arms. The tubular attachment thus provided will produce a smooth passage through which thread may be passed in sewing the button on the garment and a strong and highly efficient attaching eye is thus provided on the button. The bent end portions of the arms may be made of any appropriate length, so that the button will have a neck or shank best suited for the use for which it is intended.

The button as thus far described will have a domed body, perfectly smooth throughout with an inturned flange at its base providing a smooth finished edge about the button. In some cases it may be desired to provide an embossed or stamped design upon the body of such button. In such cases, this stamped design may be formed directly upon the blank 2 during or after the blanking operation or it may be stamped into the body of the button during or between any of the drawing and shaping operations described.

In Figures 7 and 7a I have shown a button having a body in the form of a flat disk. In these figures the body 2a corresponds to the domed body 2 of the structure of Figures 1-6, but this body is flat. It is simply blanked flat and left flat. The same blank may be used as illustrated in Figure 1. That is to say, it is provided with the tongues 3 initially formed flat, as shown in dotted lines in Figure 7, and these tongues are simply bent over against the back of the body 2a. The end portions of the tongues are bent into face contacting relation and secured together by an extruded boss, as hereinbefore described. Buttons made, according to Figures 7 and 7a, should have all edges of the blank smoothed by thumbing or otherwise, so that these edges will not be rough or sharp

enough to injure the user or fine fabrics of garments to which this button may be attached.

The button of the present invention may be made by automatic machinery in a simple and expeditious manner and through the employment of a minimum amount of labor. Inasmuch as it is strictly a one-piece button, the various elements thereof cannot possibly become disengaged from one another. It is, in effect, indestructible.

The foregoing detailed description sets forth the invention in its preferred practical form, but the invention is to be understood as fully commensurate with the appended claims.

Having thus fully described the invention, what I claim as new and desire to secure by Letters Patent is:

1. A button comprising: a body provided at opposite sides with integral tongues bent toward one another at the back of the body with the ends of the tongues upset into facial contact with one another, the abutting portion of one of said tongues being perforated and the corresponding part of the other tongue having formed therefrom a tubular boss extending through said perforation and terminally flanged to lock the abutting portions permanently to one another.

2. A button comprising: a domed body provided at its opposite sides with tongues bent toward one another at the back of the body with the ends of the tongues upset into facial contact with one another, the abutting portion of one of said tongues being perforated and the corresponding part of the other tongue having formed therefrom a tubular boss extending through said perforation and terminally flanged to lock the abutting portions permanently to one another.

3. A button comprising: a domed body provided around its periphery with an inturned flange, said flange having at its opposite sides tongues extending toward one another with their end portions bent into face abutting relation, the abutting end portion of one of said tongues being perforated and the corresponding portion of the other tongue having an integral tubular boss extending through said perforation and terminally flanged to permanently secure the tongues together.

50 HARRY C. ROBERTSON.
